US0D1012063S

(12) **United States Design Patent** (10) **Patent No.:** **US D1,012,063 S**
(45) **Date of Patent:** ** *Jan. 23, 2024

(54) **HEADSET**

(71) Applicant: **DONGGUANG LANYE ELECTRONIC TECHNOLOGY CO., LTD.**, Tanzishan Town (CN)

(72) Inventor: **Rong Xie**, Tanzishan Town (CN)

(73) Assignee: **DONGGUANG LANYE ELECTRONIC TECHNOLOGY CO., LTD.**

(*) Notice: This patent is subject to a terminal disclaimer.

(**) Term: **15 Years**

(21) Appl. No.: **29/766,632**

(22) Filed: **Jan. 17, 2021**

(51) LOC (14) Cl. **14-01**

(52) U.S. Cl.

USPC **D14/206**; D14/226

(57) **CLAIM**

The ornamental design for a headset, as shown and described.

DESCRIPTION

FIG. 1 is a front, right side, top perspective view of a headset showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the headset that form no part of the claimed design.

1 Claim, 8 Drawing Sheets
